DESIGN FOR A LENS FOR SIGNAL LAMPS

Paul C. Koeber, Bellmore, N. Y.

Application December 18, 1936, Serial No. 66,617

Term of patent 14 years

To all whom it may concern:

Be it known that I, Paul C. Koeber, a citizen of the United States, residing at Bellmore, in the county of Nassau and State of New York, have invented a new, original, and ornamental Design for a Lens for Signal Lamps, of which the following is a specification, reference being had to the accompanying drawing, forming part thereof. This application is a continuation in part of application, Serial D—54,660, filed January 2nd, 1935.

In the drawing:

Figure 1 is a plan view of a lens for signal lamps showing my new design; and,

Figure 2 is an edge view thereof.

The drawing is lined for red.

I claim:

The ornamental design for a lens for signal lamps, substantially as shown and described.

PAUL C. KOEBER.
